EMBALMING MACHINE AND ASPIRATOR

Raymond B. Grontkowski, West Hazleton, Pa.

Application September 14, 1936, Serial No. 100,708

9 Claims. (Cl. 27—24)

The invention relates to an embalming machine and more especially to an embalming, aspirating and air ejecting machine.

The primary object of the invention is the provision of a machine of this character, wherein embalming fluid can be regulated and controlled as well as the supply of different characters of solution had so that the embalming of a corpse may be expeditiously effected and at the same time enabling aspirating so as to relieve the corpse from semi-solid matter and to avoid possibility of inflation, the machine being free of interference through possibility of clogging stoppage during aspirating thus assuring perfect working of such machine while in use.

Another object of the invention is the provision of a machine of this character, wherein through selective mechanism and electric control the high or low pressure action of the machine can be arrived at and also the working operation can be changed or converted for embalming or aspirating or vice versa as well as assuring the feed of the proper embalming fluid, the quantity thereof and eliminating inflation should the feed of such fluid cease while the machine is working, thus eliminating separate operations through the use of separate and independent appliances or machines in that these operations can be carried forth by the unity of mechanism of the machine.

A further object of the invention is the provision of a machine of this character, wherein the embalming and aspirating of a corpse can be carried forth with dispatch and with certainty without liability of damage thereto resultant from the lack of supply of solution thereto during the period of embalming and also permitting the supplying of air under pressure for any purpose desired, for example, for spraying, as is necessary when embalming a corpse or whenever it be required for the use of air under pressure without the body of the corpse.

A still further object of the invention is the provision of a machine of this character, wherein drainage from the body of the corpse can be effected and should obstruction occur in such drainage the drainage line can be relieved of such obstruction for the successful working of the machine.

A still further object of the invention is the provision of a machine of this character, wherein selection by hand of the quality of the embalming fluid to be used in the corpse or the embalming operation carried forth automatically and through automatic working selectivity of the quality of the solution while during the working

of the machine, indicators and gages will identify the character of the working of such machine, these being clearly visible to an attendant of such machine.

A still further object of the invention is the provision of a machine of this character, which is comparatively simple in its construction, thoroughly reliable and efficient in its operation, compact, practically noiseless in the working thereof, readily and easily handled, portable, possessed of selectivity for embalming purposes and also aspirating of a corpse, and comparatively inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation of the machine constructed in accordance with the invention.

Figure 2 is a diagrammatic plan view showing the arrangement and parts of the machine operative for embalming and aspirating.

Figure 3 is a diagrammatic plan view of the circuit arrangement of the machine.

Figure 4 is a side elevation partly broken away and in section of a pair of solenoid controlled valves employed in the machine.

Figure 5 is a vertical sectional view through a muffler in the machine.

Figure 6 is a vertical sectional view through an automatic float valve in the fluid line of the machine.

Figure 7 is a vertical sectional view through a manually set air pressure regulator valve.

Figure 8 is a sectional view on the line 8—8 of Figure 7 looking in the direction of the arrows.

Figure 9 is a vertical sectional view through a hand operated fluid flow control valve.

Figure 10 is a sectional view on the line 10—10 of Figure 9.

Figure 11 is a fragmentary vertical sectional view through an aspirator compensating valve.

Similar reference characters indicate corresponding parts throughout the several views in the drawings.

Referring to the drawings in detail, the machine comprises a portable carriage 10 preferably supported by swiveled caster wheels 11 permitting convenient mobility for placement of the machine at convenient locations when embalming a corpse. Suitably arranged within the carriage is a pres-

50
55

sure air tank 12 of any required capacity which through the lead 13 is supplied with air under pressure from a rotary pump 14 driven by an electric motor 15, these being also suitably supported in the carriage. Within a visible chamber or compartment 16 viewed from the front of the carriage 10 is arranged several groups of containers or bottles 17 and 18, respectively, in this instance there being three bottles 17 in one group and two bottles 18 in the other group which are readily removable for filling or emptying from the chamber or compartment 16. The bottles 17 of one group are for containing embalming solutions, one bottle thereof may contain a weak solution, another a strong solution and another a medium strength solution while the bottles 18 of the other group are for drainage content from a corpse.

The carriage 10 at its front provides a main panel 19 and a supplemental panel 20, respectively, for switch, carriage and dial equipment in a manner presently described.

The electric motor 15 is arranged through electrical connection by wiring 21 with an electric power circuit 22, as, for example, that installed with a house system from a source of power supply and this connection 21 has arranged therein a main hand switch 23 coacting with a dial 24 indicative of on and off of the current as arranged on the panel 19. This switch 23 is the control for the entire machine for the feeding of current supply thereto. Upon the tank 12 are built high and low pressure controls 25 and 26, respectively, including automatic switches 27 arranged in the connections 21 so that when a determined low pressure exists within the tank 12 the motor will be stopped and also when a determined high pressure exists within the tank 12 the motor will be stopped, either one or the other of these controls 25 or 26 is selective for activity through manipulation of a regulating switch 28 hand set and arranged upon the panel 19, its setting being had by cooperation with a dial 29 common thereto.

The tank 12 is arranged with manually set air regulating valves 30, the manual setting means being indicated at 31, and these valves, respectively, are arranged in independent leads 32 and common to such valves are air pressure gages 33 which are fitted in the panel 20 and exposed from the machine for reading thereof, the manual control means 31 is fitted to the panel 20 and accessible at the front of the machine for regulation. The leads 32 have arranged therein solenoid acting valves 34 which solenoids thereof through electrical connections 35 are selectively operated from a switch 36 simultaneously coacting with the switch 28. These switches 28 and 36 are common to each other for unity action so that when either switch is set the other switch correspondingly becomes set therewith. The leads 32 join a pipe 37 having connection with an air delivery line 38 provided with an outlet nipple 39 extended from the panel 19 for attachment of a delivery hose 40 therewith. This line 38 opens into an air distributor column or cell 41 having the inlet branches 42 extending into the bottles 17 of the one group containing the embalming solutions. Arranged in the line 38 at opposite sides of the pipe 37 are solenoid controlled valves 43 in electrical connection with a two-way switch 44, it coacting with a dial 45 for the proper setting thereof and thus by this switch either solenoid valve 43 can be rendered active so that air can be discharged from the line 38 through

the nipple 39 or delivery of such air through branches 42 into the bottles 17. These branches 42 have arranged therein solenoid controlled valves 46 electrically associated with a plural contact switch 47 upon the panel 19 in association with the dial 45 and upon adjustment of said switch 47 the inflow of air to a selected bottle through a branch 42 can be had. The switch 47 is susceptible of hand adjustment and also automatically adjusted in a manner presently described. 5

Leading from the bottles 17 of the group having the embalming solution content are fluid outlet branches 48 which open into a fluid outlet distributing column or cell 50 which by a pipe 51 has communication with a float valve container 52 having the outlet main 53 provided with a coupling nipple 54 for a lead-off hose 55, the main 53 at the nipple 54 fits the panel 19. The pipe 51 is equipped with a flow meter 56 which is set in the panel 20 and also arranged in this pipe is a hand actuated flow regulating valve 57 which is carried by the panel 20 and this valve has coaction with the dial 58 for proper setting thereof and its purpose is to regulate the 20 flow of embalming solution delivered by the main 53. 25

Fitting the branches 48 are solenoid controlled valves 59, their electrical connections being common to the switch 47 which is a control therefor. In other words, when the valves 46 are controlled by the switch 47 the valves 59 are likewise controlled, thus when the switch is set in one position the valve in one branch 42 will become active and likewise the valve 59 in one of the branches 48 becomes active according to such branches common to one of the bottles and in this fashion selectivity is had for the delivery of a solution from the respective bottles 17 of the group. Within the container 52 is a float 60 carried on a valve stem 61 of a ball valve 62 controlling an air escape opening 63 and in association with the said stem 61 is a switch 64 electrically connected with a solenoid 65, its armature or core 66 having a spring dog 67 acting as a feeder for a ratchet 45 wheel 68 operatively connected with the switch 47 for automatic operation of the same. The purpose of the float 60 within the container 52 is that when the embalming solution empties from a bottle 17 the valve 62 automatically opens 50 liberating air under pressure from the pipe 51 and prevents such air passing outwardly through the main 53. The operation of the solenoid 65 takes care automatically when one bottle empties to bring another bottle 17 of the group into 55 play for the delivery of its solution contents, the bringing of the next bottle into play through the float 60 of the valve 62 becomes closed and the switch 64 opens. By the hand setting of the switch 47 when one of the bottles 17 may be 60 selected for the emptying thereof and when all bottles 17 of the group have emptied an operator then manipulates the valve 57 closing the system to avoid excessive waste of air under pressure from the tank 12, it being understood, of course, 65 that when the last bottle has been emptied the valve 62 being in an open position permits the escape of air and avoids the passing thereof through the main 53 and at this instant the said valve 67 is operated. 70

The electrical connections for the valves 43 are indicated at 69 and the electrical connections for the valves 46 and 59 are indicated at 70 while the electrical connections for the solenoid 65 are indicated at 71. 75

Leading from the bottles 18 of the other group are the branches 12 of an aspirating main 13 with a nipple end 14 for a feed hose 75, the nipple end 14 being built in the panel 19 while opening into said bottles 18 are the suction branches 16 of a suction pipe 11 which through a union 78 communicates with the pump 14 and this union has coupled therewith an atmospheric air intake pipe 79 equipped with a hand controlled air inlet regulating valve 80, the pipe 11 being at the suction side of the said pump 14. Also the union 78 has connected by a pipe 81 a vacuum gage 82 which is built in the panel 20 for the reading thereof. The valve 80 is also built in the panel 20 for hand actuation. The branches 16 have fitted therein solenoid controlled valves 83 which through electrical connections 84 are operated by a switch 85 which coacts with a dial 86 on the panel 19, the said switch 85 being also arranged thereon and through this switch selection of activity of either bottle 18 may be had for drainage of a corpse through the aspirating main 13.

The pipe 11 is a vacuum conduit and opens into a muffler 87 having a steel wool filling 88 and such muffler is located on that side of the union 78 next to the bottles 18 and is for the purpose of deadening sounds to render the apparatus in the working thereof noiseless when the said apparatus is employed for aspirating. Arranged on the panel 19 is a push button switch 89, which through electrical connections 90 has association with the solenoid valve 91, the latter being arranged for operation upon the air pipe 37 and the aspirating main 13. When the apparatus is employed for embalming, that is, the surface of the embalming solutions within the bottles 17 should it be desired to expel air to shut off the flow of the fluid or solution temporarily from said bottles the button switch 89 is operated and when this takes place the valve 91 opens thus freeing the air or causing the bleeding thereof through the aspirating main 13. Now when the apparatus is in use for aspirating should the main 13 become clogged from any cause, on pushing the button switch 89 for closing the connections 90 the valve 91 is automatically opened thereby permitting air under pressure from the tank 12 to flow through the said main 13 and thus removing any obstructions or barriers therein for the cleaning of the same, it being understood, of course, that the main 13 at this time has no connection with the corpse and such air passing therefrom is delivered to the atmosphere.

Arranged within the electrical wiring or circuit layout of the apparatus is a conventional transformer 92 and a condenser 93, respectively, the latter being directed to the solenoids for operating the valves as equipped in the apparatus. Each solenoid as employed with a valve in the apparatus is possessed of a coiled spring 94, its purpose being to automatically close the valve when the solenoid is deenergized while on energizing such solenoid the valve is open.

The bottles 17 and 18 are fitted with removable caps or covers 95, each provided with a suitable handle 96 and such caps on removal thereof permit the emptying or filling of the said bottles as well as enabling convenient cleaning of the same. It is, of course, understood that the branch leads to and from the bottles are of a kind that permit the removal and placement of such caps or covers.

The valve 80 is of the needle type to permit close adjustment thereof.

The switches 27 preferably are of the snap type for quick acting and are adjustable for pressure regulation through adjusting screws 97.

In the operation of the apparatus when it is desired to carry forth the embalming process of a corpse the attendant of the machine sets the same for the desired air pressure in conformity with conditions present then through controls the air under pressure is admitted or delivered to the bottles 17 containing the embalming solutions and such delivery of a desired solution from any one of the bottles can be selected for delivery either by hand or automatically and the selectivity enables these solutions to be delivered in sequence or individually. When one bottle 15 empties the other bottle is brought into action and the flow of the embalming fluid is regulated by the valve 57.

Now for aspirating under activity of the pump which serves as a suction device a vacuum will be created in the main 13 so that drainage of the content of the corpse can be had with the deposit of such drainage made within the bottles 18. The valve 80 serving to regulate the atmospheric air admitted to the pump 14 thus controls the vacuum effected in the main 13.

Should it be required to service the pipe 38 with air under pressure the valves 43 are operated so that air under pressure can be delivered through the pipe 38 to the point of consumption.

Should it be required to shut off the supply of embalming solution from the bottles 17 the button 89 will be actuated and the air diverted from the bottles and thereby temporarily preventing the flow of such solution through the main 53. Then should the main 13 become clogged or choked for any reason by operating the button 89 such main can be cleared due to the flow of air under pressure thereto.

What is claimed is:

1. An apparatus of the kind described comprising a compressed air tank, a combined motor and compressor, connections between the compressor and said tank, automatic high and low pressure controls associated with the tank and coacting with the motor for the stopping thereof, means for effecting selective activity of said controls, a plurality of fluid receptacles, and means for directing air under pressure from the tank to the receptacles.

2. An apparatus of the kind described comprising a compressed air tank, a combined motor and compressor, connections between the compressor and said tank, automatic high and low pressure controls associated with the tank and coacting with the motor for the stopping thereof, means for effecting selective activity of said controls, a plurality of fluid receptacles, means for directing air under pressure from the tank to the receptacles, and means for delivering fluid from the receptacles.

3. An apparatus of the kind described comprising a compressed air tank, a combined motor and compressor, connections between the compressor and said tank, automatic high and low pressure controls associated with the tank and coacting with the motor for the stopping thereof, means for effecting selective activity of said controls, a plurality of fluid receptacles, means for directing air under pressure from the tank to the receptacles, means for delivering fluid from the receptacles, and automatic means active on the emptying of one receptacle for bringing another receptacle into action for delivery of its contents.

4. An apparatus of the kind described com-
